UNITED STATES PATENT OFFICE.

ANNIE MARY OPPENHEIM, ADMINISTRATRIX OF JOSEPH OPPENHEIM,
DECEASED, AND HENRY SYNCK, OF MARIA STEIN, OHIO.

FERTILIZER-DISTRIBUTER.

SPECIFICATION forming part of Letters Patent No. 712,581, dated November 4, 1902.

Application filed January 13, 1902. Serial No. 89,609. (No model.)

To all whom it may concern:

Be it known that JOSEPH OPPENHEIM, deceased, late a resident of Maria Stein, county of Mercer, and State of Ohio, and HENRY 5 SYNCK, of the same place, citizens of the United States, did invent certain new and useful Improvements in Fertilizer-Distributers; and we, ANNIE MARY OPPENHEIM, administratrix of the estate of JOSEPH OPPENHEIM, 10 deceased, late a citizen of the United States, and HENRY SYNCK, do hereby declare the following to be a full, clear, and exact description of the invention, such as will enable others skilled in the art to which it appertains 15 to make and use the same.

This invention relates to apparatus for spreading manure, compost, and the various kinds of fertilizers used for enriching land, the purpose being to provide a novel form of 20 actuating mechanism, means for throwing the actuating mechanism into and out of gear at the will of the operator, automatic means for throwing the machine out of action when the fertilizer has been exhausted, so as to prevent 25 injury to the working parts, a stripper for clearing the drag-chains, and, lastly, to improve the general construction, whereby better results are attained.

For a full description of the invention and 30 the merits thereof and also to acquire a knowledge of the details of construction of the means for effecting the result reference is to be had to the following description and drawings hereto attached.

35 While the essential and characteristic features of the invention are susceptible of modification, still the preferred embodiment of the invention is illustrated in the accompanying drawings, in which—

40 Figure 1 is a vertical longitudinal section of a fertilizer-distributer embodying the essential features of the invention. Fig. 2 is a detail view showing the relation of the stripper to the drag-chains and the sprocket-wheel around which the drag-chain passes. Fig. 3 45 is a side view of the rear portion of the machine. Fig. 4 is a view of the reverse side of the machine, the intermediate portion of the body and running-gear being broken away. Fig. 5 is a transverse section on the line X X 50 of Fig. 3 looking toward the rear, as indicated

by the arrow. Fig. 6 is a detail section about on the line Y Y of Fig. 4, showing the parts on a larger scale. Fig. 7 is a sectional detail view on the line Z Z of Fig. 4 looking to the left, showing the operating-lever and the guide coöperating therewith. Fig. 8 is a detail view of the vibrating lever for intermittently actuating the drag-chains, the lever for throwing said mechanism out of gear, the 60 trip for automatically unshipping the feed mechanism and a portion of the ratchet-wheel and the detent-pawl coöperating therewith. Fig. 9 is a detail view of the means for throwing the beaters into and out of gear. Fig. 10 65 is a detail perspective view of the lever and rod for throwing the unshipping-lever into and out of action. Fig. 11 shows a front and side view of one of the teeth of the beaters. Fig. 12 is a top plan view of the parts shown 70 in Fig. 2, the drag-chain and the part to which the stripper is attached being omitted.

Corresponding and like parts are referred to in the following description and indicated in all the views of the drawings by the same 75 reference characters.

The wagon-body 1 may be of any size and desired construction and is mounted upon ground-wheels 2 and 3, one of which constitutes the driver for imparting motion to the 80 distributing and spreading mechanisms. The running-gear upon which the body 1 is mounted may be of any pattern best adapted for the purpose, and the drive-wheel is provided around its rim with cogs to prevent slipping 85 in soft and marshy land. The distributing mechanism is located at the rear end of the body 1, and the working elements thereof are suitably mounted. A follower 4 and drag-chains 5 are adapted to travel over the bottom of the body 1 between the sides, so as to advance the fertilizer to the distributing mechanism. This follower 4 is rigidly attached to the drag-chains 5, which pass around sprocket-wheels 6 and 7 at opposite ends of 90 the wagon-body, the lower portion of the drag-chains being protected and supported by guides 8, attached to the bottom of the body 1 at or near each edge. The guides 8 are upwardly deflected at a point between 95 their ends, as shown at 9, to provide a space 100 to receive the front wheels 2, as shown by

the dotted lines in Fig. 1, when turning the machine. A trip 10 (see Fig. 6) is attached to one of the drag-chains and is adapted to automatically throw the feeding mechanism 5 out of gear, as will be explained more fully hereinafter. The sprocket-wheels 7 are fastened to revolve with a shaft 11 near the rear end of the machine and are intermittently actuated to advance the follower 4 step by 10 step. A ratchet-wheel 12 (see Figs. 4 and 8) is secured to one end of the shaft 11, and receives motion from a vibratory lever 13.

A stripper 14 (see Fig. 2) is provided for each sprocket-wheel 7 and drag-chain 5, and 15 is loosely hung under one end of the bottom A or other convenient portion of the wagon-body, so as to follow the movements of the shaft 11 and the sprocket-wheel 7 with which it co-operates. The opposite end portion of 20 the stripper is curved and gradually widened to provide a cam portion 15, which serves to gradually disengage the links of the drag-chains from the teeth of the sprocket-wheels 7, thereby preventing the sprocket-chain from 25 wrapping around the sprocket-wheel. As shown most clearly in Fig. 2, the strippers 14 are mounted independently of the shaft 11, and its bearings are disposed so as to effect the purposes aforesaid in the best manner possible. A shaft 16 (see Figs. 1 and 9) extends 30 transversely of the machine and receives the distributing-cylinder 17 and is provided at one end with a gear-wheel 34, which is operated by means of a sprocket-chain 19, receiving motion from a toothed rim 20, attached to 35 or forming a part of the drive-wheel 3. The lower portion of the drive-chain 19 passes over an idler 21, which is so mounted as to admit of any slack in the drive-chain being taken 40 up. The upper end of the drive-chain 19 is supported by means of an idler 19^a, mounted upon a stud 19^b, projected laterally from a side of the body 1. A gear-wheel 22 is secured to the opposite end of the shaft 16 for 45 rotation therewith, and a drive-chain 23 connects the gear-wheel 22 with a corresponding gear-wheel 24 at one end of a shaft 25, journaled in the outer end of rear extensions 26. Blades 27 are attached to the shaft 25 and are 50 arranged in such a manner as to spread the fertilizer in the operation of the machine. The shaft 25 and blades 27 constitute the spreader, whereby the fertilizer is distributed over a track greater than the width of the 55 body 1 or the length of the distributing-cylinder 17. This is due to the arrangement of the blades, which are set obliquely to their plane of rotation, as indicated in Figs. 1 and 3, the blades inclining from the center of the 60 shaft in opposite directions to spread the fertilizer laterally.

The upper beater for lightening and pulverizing the upper portion of the fertilizer is located at a higher elevation than the distributing-cylinder and comprises a shaft 28, body 29, and teeth 30. A sprocket-wheel 31 is secured to an end portion of the shaft 28,

and is connected, by means of a drive-chain 32, with the sprocket-wheel, preferably fastened in such a manner upon an end portion of the 70 shaft 16 to rotate with the same. The gear-wheel 34 has its teeth in mesh with the upper portion of the drive-chain 19 and is operated thereby for rotation of the beaters and distributing-cylinder. Sprocket-wheels 75 33 and 34 have, preferably, each a one-half clutch, which can be engaged to control the actuation of the distributing and beater cylinders. These half-clutches constitute the clutch 35, which is operated by means of a 80 shipper-lever 36, connected by means of a rod 37 with a lever (not shown) within convenient reach of the driver's seat to admit of the machine being thrown into and out of gear, as desired. 85

The vibratory lever 13 is mounted upon an end portion of the shaft 11 and is provided with a pawl 38 for engagement with a tooth of the ratchet-wheel 12. A pitman 39 connects the upper part of the lever 13 with a wrist-pin 40 of the gear-wheel 22, whereby said lever is oscillated. Retrograde movement of the shaft 11 is prevented by means of the detent-pawl 41, which engages with a tooth of the ratchet-wheel 12. When the lever 13 is moved 90 forward at its upper end, the pawl 38 rides upon the teeth of the ratchet-wheel, and as the lever moves rearward the pawl 38 engaging with a tooth of the ratchet-wheel causes the latter to rotate and imparts a corresponding 95 movement to the follower 4 through the instrumentality of the drag-chains 5 and sprocket-wheel 7, as will be readily comprehended. When the shipper-lever 36 is actuated to 100 throw the clutch 35 out of mesh, the sprocket-gears 33 and 34 are separated and the shaft 16 does not rotate. Hence no movement is imparted to the lever 13, and as a consequence the feeding mechanism is in a state of rest. It will thus be seen that unshipping of the 105 clutch 35 throws the entire mechanism out of action. It is desirable at times to throw the feeding mechanism out of gear without stopping the action of the distributing cylinder or beater, and for this purpose the following 110 means have been devised and consist, essentially, of the unshipping-lever 42, pivoted to the vibratory lever 13 at 43, and having a cam-head 44 and a curved end 45, terminating in a lateral extension 46, projected into the path 115 of the trip 10, to be engaged thereby for throwing the pawl 38 out of the path of the teeth of the ratchet-wheel 12 when the fertilizer has 120 been exhausted. This lever 42 occupies the position substantially as shown by the full 125 lines in Fig. 8, so as not to interfere with the pawl 38, but when moved to the position indicated by the dotted lines in Fig. 8 the end 44 comes in contact with the pawl 38 and 130 throws it out of the path of the ratchet-wheel 12, thereby preventing further operation of the feeding mechanism. The lever 42 is adapted to be actuated automatically by the trip 10 or at the will of the operator. For the lat-

ter purpose a lever 47 is provided and is connected by means of a rod 48 with the lever 42. This lever 47 is conveniently located for operation from the driver's seat and is preferably an integral part of the rod 48. A bracket 49 is secured to a side of the wagon-body, and its upper end is forked, as shown most clearly in Fig. 7, to receive the front end of the rod 48 to hold the latter in place and give direction thereto when moved forward or backward. A crimp is formed in the forward portion of the rod 48, so as to provide a tooth 50, which is adapted to engage over the front side of the bracket 49 in advance of the fork and hold the unshipping-lever 42 in the position shown by the dotted lines in Fig. 8, thereby holding the feeding mechanism out of gear until reset by the operator. The teeth of the beater and distributing-cylinder are constructed substantially as shown in Fig. 11, their outer ends being tapering and flattened for the better engagement with the fertilizer in the distribution thereof.

The fertilizer, manure, compost, lime, guano, plaster, or the like, is supplied to the body, the follower having been moved either to the front end or to any point in the length of the body. The actuating mechanism being in gear and the machine drawn over the field, the follower is advanced step by step to carry the fertilizer to the distributing mechanism, which spreads the same on the land. The fertilizer is taken up by the distributing-cylinder 17 and is loosened and lightened by the beater and is spread laterally by the blades 27. Should it be required to throw the machine out of gear, it is only necessary to disengage the clutch 35. The feeding mechanism may be thrown out of gear without interrupting the operation of the distributing-cylinder or beater by operation of the unshipping-lever 42. When the fertilizer is nearly exhausted, the trip 10 will come in contact with the bent end 46 of the lever 42 and automatically throw the pawl 38 out of engagement with the teeth of the ratchet-wheel 12, whereby injury to this part of the machine is wholly obviated.

The body 1, with the feeding and distributing mechanisms, is mounted upon the running-gear so as to be removed therefrom to admit of the running-gear being used with wagon-bodies or hay-racks or for any other purpose. The body 1 when in position is secured against displacement by any substantial means, a clip 53 (see Fig. 3) being employed. The upper beater is adjustable toward and from the distributing-cylinder, and for this purpose is carried by pivoted arms 51, which are secured by means of a pin inserted in any one of a series of openings 52. This beater is located in front of the distributing-cylinder to relieve the latter of the upper portion of the load and enable a more thorough pulverizing of the fertilizer.

The beaters 17 and 29 and spreader 27 are necessary to distribute manure, compost, and

like fertilizer; but for scattering plaster, lime, guano, and kindred pulverulent substance a distributor, as 54, (see Fig. 1,) is used, and consists of a flat plate mounted for rotation and arranged below the rear end of the bottom of the body 1, said distributor being rotated by means of a chain 55 from the shaft 25.

Having thus described the invention, what is claimed as new is—

1. In a fertilizer-distributer of the character described, the combination with a body holding the fertilizer in bulk, a distributing mechanism at one end of the said body, a drag-chain and follower for advancing the fertilizer to the distributing mechanism, actuating means for the drag-chain comprising a shaft and sprocket-wheel, and a stripper 85 mounted independently of the said shaft but guided by the sprocket-wheel and arranged to disengage the links of the drag-chain from the teeth of the sprocket-wheel, substantially as set forth.

2. In a fertilizer-distributer, and in combination with the distributing mechanism, means for advancing the fertilizer to the distributing mechanism, and actuating means for the feeding means comprising a ratchet-wheel, a vibrating lever and a pawl, an unshipping-lever adapted to have a portion extended in the path of the said pawl and throwing it out of the path of the teeth of the ratchet-wheel, and means for operating the said ratchet-wheel, substantially as set forth.

3. In a fertilizer-distributer of the character described, and in combination with the distributing mechanism, a feeder and actuating means therefor comprising a vibrating lever, 105 pawl and ratchet-wheel, an unshipping-lever pivoted to the vibrating lever and having a cam portion to be brought in contact with the pawl to throw it out of the path of the ratchet-wheel, an operating-lever, a rod connecting 110 the operating-lever with the unshipping-lever, and means for holding the parts in the desired position, substantially as specified.

4. In a fertilizer-distributer of the character described, the combination of the distributing mechanism, a feeder comprising a follower and a drag-chain, means for intermittently actuating the feeder comprising an oscillatory lever, a pawl and a ratchet-wheel, an unshipping-lever pivoted to the said oscillatory lever, and a trip attached to the drag-chain for automatically operating the unshipping-lever to throw the feeder-actuating mechanism out of gear, substantially as set forth.

5. In combination, a distributing-cylinder, 125 gears mounted upon the shaft of the distributing-cylinder, a clutch for throwing said gears into and out of mesh with each other and the said shaft, a beater connected for rotation with one of the said gears, a feeder, 130 actuating mechanism for the feeder operated by means of the shaft of the distributing-cylinder, means for throwing the feeder-actuating mechanism out of gear independently of

the distributing-cylinder, and a spreader actuated from the shaft of the distributing-cylinder, substantially as set forth.

6. In a fertilizer-distributer, the combination with the running-gear, and the body for holding the fertilizer in bulk removably fitted upon the running-gear, of a follower and a drag-chain applied to the body, and a track beneath, adjacent and attached to the bottom 10 of the body for supporting the lower portion of the drag-chain, said track extending over the front and rear axles of the running-gear and having an upwardly-deflected portion to admit of the front wheels turning thereunder, 15 substantially as specified.

7. In a fertilizer-distributer, the combination with the body holding the fertilizer in bulk, a follower and a drag-chain, a track beneath the bottom of the body for supporting the lower portion of the drag-chain and having an upwardly-curved portion to clear the front wheels when making a short turn, 20 substantially as specified.

8. In a fertilizer-distributer, the combination with the body holding the fertilizer in 25

bulk, and means for advancing the fertilizer to the rear end of the body, a distributing-cylinder for pulverizing and delivering the lower portion of the fertilizer, and an upper beater set in advance of the distributing-cylinder for relieving the latter of the weight of the upper portion of the fertilizer and pulverizing the same, substantially as specified. 30

9. In a fertilizer-distributer, the combination with the body holding the fertilizer in bulk, and means for advancing the fertilizer to the rear end of the body, a beater, and a spreader arranged below the space formed between the said beater and the rear end of the bottom of the body, substantially as set 35 40 forth.

In testimony whereof we affix our signatures in presence of two witnesses.
